Attorneys.

UNITED STATES PATENT OFFICE.

RUPERT B. SMART, OF CHICAGO, ILLINOIS.

PRINTER'S GALLEY.

Application filed December 19, 1927. Serial No. 240,950.

My invention relates to a printer's galley or chase and has for one purpose to provide such a galley wherein slugs, and particularly address slugs, may be positioned and spaced.

5 Other objects will appear from time to time in the course of the specification and claims.

I illustrate my invention more or less diagrammatically in the accompanying drawings, wherein—

- 10 Figure 1 is a plan view;
- Figure 2 is a side elevation;
- Figure 3 is a section on the line 3—3 of Figure 1; and
- Figure 4 is a section on the line 4—4 of

15 Figure 1.

Like parts are indicated by like symbols throughout the specification and drawings.

- A indicates the bottom or body portion of the device having along its opposite edges
- 20 the upwardly turned flanges B, B, B¹, B¹ indicate terminal flanges at the end of the trough. Both members B, and a portion of the member A adjacent thereto, are penetrated by a plurality of parallel slots C.
- 25 The metal between each such bar is upset or pushed inwardly as at C¹, to form a plurality of spacing stops, it being understood that the stops at opposite sides of the body member are identically spaced and aligned.
- 30 In the use of my device slugs, such as D, which may include one or more lines, are dropped into the space between the stop members C. The slugs rest on the bottom of the device and are held against lateral movement by the sides and are held against
- 35 longitudinal movement by the stops.

The result is a peculiarly simple, efficient and cheaply and easily manufactured unit whereby a large number of addresses, for example, may be positioned for use with a press. The slugs are easily inserted and removed and changes of arrangement can be quickly and easily made.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

I claim:

- 55 1. As a new article of manufacture, a

printer's galley comprising a sheet metal trough having a flat bottom, and sides upwardly extending therefrom at right angles thereto, and spacing members upset from and inwardly projecting from said sides. 60

2. As a new article of manufacture, a printer's galley comprising a sheet metal trough having a flat bottom, and sides upwardly extending therefrom, and spacing members upset from and inwardly projecting from said sides. 65

3. As a new article of manufacture, a printer's galley comprising a sheet metal trough having a flat bottom, and sides upwardly extending therefrom and spacing members upset from and inwardly projecting from the sides and the adjacent portions of the bottom. 70

4. As a new article of manufacture, a printer's galley comprising a sheet metal trough having a flat bottom portion, sides upwardly projecting therefrom, said sides being penetrated by a plurality of parallel slots, the alternate tongues of metal between such slots being inwardly upset. 75

5. As a new article of manufacture a printer's galley comprising a sheet metal body portion and a plurality of upwardly extending spacing members positioned along the opposite edges thereof, said spacing members being adapted to receive and space printing slugs. 80

6. As a new article of manufacture, a printer's galley comprising a sheet metal body portion and a plurality of upwardly extending spacing members positioned along the opposite edges thereof, said spacing members being adapted to receive and space printing slugs, said spacing members being integral with the body portion. 90

7. As a new article of manufacture, a printer's galley comprising a trough having a bottom portion adapted to support the slugs used therewith and having side portions upwardly projecting from said body portion, adapted to engage the ends of said slugs, and a plurality of spacing stops inwardly projecting from said side members. 100

Signed at Chicago, county of Cook, and State of Illinois, this 16th day of December, 1927. 105
